UNITED STATES PATENT OFFICE.

WILLIAM FRANCIS BATTERS, OF CLICK, TEXAS.

WIRE-SPlicer.

SPECIFICATION forming part of Letters Patent No. 374,650, dated December 13, 1887.

Application filed October 11, 1887. Serial No. 252,058. (No model.)

To all whom it may concern:

Be it known that I, WILLIAM FRANCIS BATTERS, a citizen of Great Britain, residing at Click, in the county of Llano and State of Texas, have invented a new and useful Improvement in Wire-Splacers, of which the following is a specification.

My invention relates to improvements in wire-splacers; and it consists in a certain novel construction hereinafter described and claimed.

In the accompanying drawings, Figures 1 and 2 are perspective views illustrating the manner of using my device, and Fig. 3 is a longitudinal section of the splicer detached.

Referring to the drawings by letter, A designates a cylindrical or other bar or rod, which serves as a handle for the device, and at its lower end is provided with the integral offset B, which is provided with a central perforation, C, as shown. A recess, D, is formed in the side of the handle and top of the offset, and in the angle formed by the offset and the handle I provide the semicircular groove E, as shown.

In operation the ends of the wires are laid alongside each other and grasped by a wrench, as clearly shown in Figs. 1 and 2. The extremities of the wires are then bent at right angles to the body of the same, and the splicer is then placed so that the offset B will engage the bent end of one wire, while the groove E will fit around the body or length of the other wire. The wrench is now held in one hand

while the splicer is rotated by the other upon the wire in the groove E as a center. The rotation of the splicer causes the end of the wire carried thereby to coil around the other wire, as shown in Fig. 2, the end of the coil fitting in the recess D. When the wire has been thus treated on one side of the wrench, the splicer is applied to the wire on the other side of the wrench, which is similarly treated, after which the splicer and wrench are removed and the splice is complete.

From the foregoing it will be seen that I have produced a very simple and efficient device, and its advantages will be readily appreciated.

Having thus described my invention, what I claim, and desire to secure by Letters Patent, is—

A wire-splicer consisting of a handle, A, having an integral lateral offset, B, at one end, provided with a transverse perforation, C, formed substantially in line with the handle, a groove, E, being formed in the angle formed by the lateral offset B and the handle A, and an enlarged recess, D, being formed in the side of the handle and top of the offset concentrically with the groove E, substantially as specified.

In testimony that I claim the foregoing as my own I have hereto affixed my signature in presence of two witnesses.

WILLIAM FRANCIS BATTERS.
